Henry H. Wait.

By G. A. Gray & Wait

UNITED STATES PATENT OFFICE.

HENRY H. WAIT, OF CHICAGO, ILLINOIS.

BRUSH STRUCTURE.

1,363,758.

Specification of Letters Patent. Patented Dec. 28, 1920.

Application filed August 22, 1917. Serial No. 187,646.

To all whom it may concern:

Be it known that I, HENRY H. WAIT, citizen of the United States, residing at Chicago, in the county of Cook and State of Illinois, have invented a certain new and useful Improvement in Brush Structures, of which the following is a full, clear, concise, and exact description.

My invention relates to brush structures for dynamo electric machines and has for its general object the provision of a construction whereby a coiled tension spring may be made effective in applying feeding pressure to the contacting member of the brush structure. My employment of a tension coiled spring enables me to provide a safe limit to which the feeding pressure of the spring may be increased, this being an advantage over a feeding compression coiled spring. My invention also has for its object the provision of an improved means for associating the spring with the contacting member and the brush holder. My invention in all of its characteristics will be fully set forth by reference to the preferred embodiment thereof shown by the accompanying drawing, in which—

Figure 1 is a side elevation illustrating a brush structure in working position, a feeding member being indicated in an alternative position by dotted lines, to permit the contacting member of the brush structure to be removed;

Fig. 2 is a side elevation illustrating an arrangement of parts whereby the contacting member of the brush structure, while still in assembly with the balance of the structure, may be held in position without being forced against the commutator (or rotating terminal structure of the dynamo), so that the commutator may be sand-papered, or have other work done upon it, while the brushes are held out of working contact with it;

Fig. 3 is a plan view of the brush structure as it appears in Fig. 1, and

Fig. 4 is a view on line 4—4 of Fig. 1.

Like parts are indicated by similar characters of reference throughout the different figures.

The brush structure illustrated includes a brush holder 1 that has a split sleeve portion 2 whereby the brush holder may be supported upon a cylindrical stud 3 (fixedly mounted on a suitable carrier, not shown). The sleeve has projecting ears 4 that are

located on opposite sides of the gap or split 5 in the sleeve. The stem of the clamping bolt 6 passes freely through the outer ear 4 into threaded engagement with the other ear. 60 Upon loosening the bolt the brush holder may be swung to any suitable position, in which it is secured by tightening the bolt to clamp the sleeve 2 upon the stud 3. The end of the brush holder, opposite that end 65 which is fixed to the stud 3, is provided with a sleeve 7 which is inclined or otherwise suitably directed toward the commutator 8. The contacting member 9 of the brush structure is of any preferred or suitable construction and is disposed in the bore of the sleeve 7 in which the contacting member is free to move lengthwise of such sleeve 7.

The contacting member 9 of the brush structure is maintained in contact with the 75 commutator by means of a coiled or helical tension spring 10. One end of the spring is anchored to a side of the holder 1 that is nearer the commutator, this anchorage being desirably effected by engaging the helices 80 at the inner end of the spring with corresponding helical grooves or threads in the holder. The helices at the outer or free end of the spring are in threaded engagement with a nut 11 that is disposed within the bore 85 of the spring. The threaded stem of an adjusting screw 12 is in engagement with the threaded bore of the nut. The nut will not readily turn in the spring 10, so that the screw may be turned with respect to the nut 90 to adjust the amount of the screw that projects beyond the spring. The head of the screw 13 is provided with ridges or knife edges 14 which bear upon the feeding bar 15 that is employed for transmitting the 95 pressure of the spring to the contacting member. One end of the feeding bar rests upon the upper end of the contacting member 9 and has knife edge engagement therewith, while the other end of the bar rests 100 upon and has knife edge engagement with a portion of the brush holder that is adjacent the mounting stud 3, the knife edges 14 upon the screw head 13 engaging an intermediate portion of this bar. The feeding bar 15 has 105 a transverse depression 15' constituting the home seat for the knife edges 14 to prevent the screw head from turning after it is adjusted. The feeding bar is desirably of U-shape, one end being substantially in the 110 line of the feeding movement of the contacting member 9 and engaging the outer end

of this member. The other end of the feeding bar is formed with a knife edge 16, which is normally seated in a notched seat 17 in the adjacent side of the holder 1. The areas 5 of contact between the ends of the feeding bar and the parts engaged thereby are small, as is also the area of contact of the screw head 13 that occurs at the knife edges 14 with the intermediate portion of the feeding 10 bar upon the outer face of such bar. The feeding bar is thus very free to shift its position as the contacting member 9 is fed toward the commutator with minimum attendant friction. The outer end of the contacting member 9 is beveled from and at an acute angle with respect to the forward or leading face of the contacting member toward the rear or trailing face of the contacting member, this beveling being in a 15 direction to enable the feeding bar to press the contacting member laterally in the direction in which the commutator turns and presses this contacting member against the part or side of the brush holder sleeve that 20 engages the forward or leading face of the contacting member.

The screw head 13, by reason of its engagement with the feeding bar 15, places the spring 10 under tension, the degree of which 25 is regulated by turning the screw head. The extent to which the tension of the spring is increased is limited by the feeding bar which is interposed between the outer end of the spring and the knife edges 14 upon the screw head. By thus limiting the extent to which the tension of the spring may 30 be increased a safe limit is defined for the spring pressure which may be applied to the contacting member, this being an important 35 advantage in the employment of a tension spring, over a compression spring, for exerting feeding pressure upon the contacting member.

It will be observed that the end of the 40 feeding bar that engages the brush holder is wider than the end of the feeding bar that engages the contacting member so that there is, in effect, a tripod engagement of the feeding bar with the brush holder and 45 contacting member that enables this bar to assume its proper level or position which is maintained by the action of the spring pressing upon the bar.

If it should be desired to remove the contacting member the feeding bar, which is arranged to be bodily movable, is placed in the position shown by the dotted lines, the feeding end of the feeding bar being shifted onto the holder, while the other end of the 50 feeding bar is slipped into a notch 18 that is located in the holder at one side of the sleeve 2. If it should be desired to hold the contacting member in assembly with the brush holder without exerting spring pressure upon the outer end of the contacting 55

member, the feeding bar may be placed in the position indicated in Fig. 2, where the feeding bar is illustrated as engaging a side of the contacting member with sufficient pressure to maintain this member in assembly with the brush holder but without effecting any feeding movement of the contacting member. While the contacting member is thus held the commutator may be readily sandpapered and otherwise worked upon. A binding screw 19 is provided in the holder in case a pig-tail is to be connected between the holder and the contacting member.

While I have herein shown and particularly described the preferred embodiment of my invention, I do not wish to be limited to the precise details of construction shown, as changes may readily be made without departing from the spirit of my invention, but having thus described my invention I claim as new and desire to secure by Letters Patent the following:

1. A brush structure for dynamo electric machines including a brush holder; a contacting member carried by the brush holder and whose outer end is beveled from and at an acute angle with respect to the leading face of the contacting member toward the trailing face of the contacting member; a bodily movable feeding bar having knife edge engagement with both the beveled outer end of the contacting member and the holder; and a coiled tension spring connected at one end with the holder and having knife edge engagement with the outer face of the feeding bar intermediate the ends of such bar.

2. A brush structure for dynamo electric machines including a brush holder; a contacting member carried by the brush holder; a feeding bar having one end in engagement with the brush holder and the other end in engagement with the contacting member, one of these ends having knife edge engagement with the part it engages, this end being wider than the other end of the feeding bar; and a spring engaging a mid portion of the feeding bar to hold its ends in engagement.

3. A brush structure for dynamo electric machines including a brush holder; a contacting member carried by the brush holder; a feeding bar adjustable upon the brush holder to have one end engageable with the outer end of the contacting member or with a side face of the contacting member or with the brush holder directly at one side of the space that receives the contacting member; and a spring which maintains the feeding bar in each of its three adjustments.

4. A brush structure for dynamo electric machines including a brush holder; a contacting member carried by the brush holder; a bodily movable feeding bar having knife edge engagement with the contacting mem-

ber and the holder; and a coiled tension spring connected at one end with the holder and having knife edge engagement with the outer face of the feeding bar intermediate 5 the ends of such bar.

5. A brush structure for dynamo electric machines including a brush holder; a contacting member carried by the brush holder; a feeding bar which is bodily movable to 10 enable it to have different positions upon

the holder that is notched at different places to hold the bar in different positions; and a spring for maintaining the bar in assembly with the holder in the different positions of the bar. 15

In witness whereof, I hereunto subscribe my name this 18th day of August, A. D. 1917.

HENRY H. WAIT.
